DESIGN FOR A BRIEF CASE

Richard H. Arbib, Huntington Woods, Mich., assignor to United States Rubber Company, New York, N. Y., a corporation of New Jersey

Application December 9, 1947, Serial No. 143,055

Term of patent 14 years

(Cl. D87—5)

To all whom it may concern:

Be it known that I, Richard H. Arbib, a citizen of the United States of America, residing in Huntington Woods, county of Oakland, and State of Michigan, have invented a new, original, and ornamental Design for a Brief Case, of which the following is a specification, reference being had to the accompanying drawing, forming part thereof, wherein:

Fig. 1 is a side view of a brief case embodying the design, the handle being shown raised.

Fig. 2 is an end view of the brief case shown in Fig. 1.

Fig. 3 is a side view similar to Fig. 1, except that the handle is depressed.

Fig. 4 is an end view similar to Fig. 2, except that the brief case is partly open.

Fig. 5 is a top plan view of the brief case;

Fig. 6 is a bottom view of the brief case; and

Fig. 7 is a sectional view taken on line 7—7 of Fig. 1.

The opposite side and end of the brief case are the same in appearance as those shown.

I claim:

The ornamental design for a brief case, substantially as shown and described.

RICHARD H. ARBIB.
